SAFETY SWITCH

Fred Colby, Morristown, N. J.

Application January 20, 1942, Serial No. 427,517

7 Claims. (Cl. 260—52)

This invention relates to a safety switch for use in electrical circuits, such as are employed in lighting, household appliances, and particularly conveyances, such as motor boats, automobiles and the like.

The safety switch according to this invention is an improvement over that disclosed in my Patent No. 2,208,179, July 16, 1940.

The improved switch herein disclosed, in common with that of my patent, embodies a fluid circuit interrupter of such construction as to be effective to interrupt an electrical circuit by either manual or automatic operation.

The general switch construction according to my prior patent embodies a casing enclosing a vertically elongated chamber, opposed arcuate electrodes embedded in the walls of the casing and having spaced plane contact surfaces close to opposite sides of a plane including the axis of the casing, a fluid conducting medium in the chamber, and a vertically movable piston within the chamber for alternately forcing the fluid into and out of contact with the electrodes for making and breaking the circuit respectively.

The particular arcuate form of the electrodes provides for automatic breaking of the circuit upon overturning of the switch to a position substantially at right angles to its normally vertical axis in that the fluid would rest within the hollow of one or the other of the arcuate electrodes with its surface below the adjacent contact surfaces of the electrodes. Such a construction however, is substantially limited in its range of efficiency, for the reason that the circuit is automatically interrupted only upon tipping of the switch casing one way or the other, substantially in a single plane at right angles to the planes of the opposed electrode contact surfaces.

In other words, the switch in accordance with my patented construction when used in automobiles for instance, would be effective for automatic interruption of the circuit only upon overturning of the automobile on one side or the other thereof for the reason that the electrode contact surfaces were necessarily maintained in planes parallel to the medial longitudinal axis of the automobile.

A primary object of this invention is therefore to provide a more flexible and effective control for a switch as embodied in my patent whereby the circuit may be manually or automatically interrupted upon overturning of the normally vertically disposed switch casing at any angle circumferentially of the axis thereof with a further cooperating manual control for closing of

the circuit when it is broken in any overturned position of the casing.

5 A further object of the invention is the provision of a switch of the above noted character which is relatively simple, compact and rugged in construction, and which will retain its operating efficiency for an indefinite period of time.

Other objects and advantages of the invention will appear as the description of the appended drawings proceeds.

I desire to have it understood however, that I do not intend to limit myself to the specific details shown or described, but that I intend to include as part of my invention, all such obvious changes and modifications as fairly fall within the scope of the claims.

In the drawings, forming a part of the specification,

Fig. 1 is a vertical sectional view through a 20 switch in accordance with one embodiment of the invention.

Fig. 2 is a transverse sectional view of the 25 switch taken substantially in the plane of line 2—2 of Fig. 1.

Fig. 3 is a view similar to Fig. 2, but showing the switch as having been rotated through an angle of 90°.

Fig. 4 is a view similar to Fig. 1, disclosing a 30 modified embodiment of the invention.

Fig. 5 is a transverse sectional view of the 35 switch of Fig. 4 and taken substantially in the plane of line 5—5 thereof.

Fig. 6 is a fragmental vertical sectional view 40 disclosing a modified form of swivel mounting for the switch casing.

Fig. 7 is a fragmental elevational view 45 disclosing a modified form of piston operating and switch casing rotating means.

Fig. 8 is a top plan view of the structure 50 illustrated in Fig. 7.

Fig. 9 is a view partly in elevation and partly 55 in vertical section disclosing a further modified form of piston operating and switch casing swiveling means.

Fig. 10 is an elevational view of the switch of Fig. 9 as observed from the right thereof.

Fig. 11 is a view partly in elevation and partly 50 in vertical section disclosing a further modified form of the invention.

Fig. 12 is a horizontal sectional view as 55 observed in the plane of line 12—12 in Fig. 11.

Fig. 13 is a reduced fragmental view partly in elevation and partly in vertical section disclosing a still further form of the invention.

Referring to the drawings in detail, and first

to Figs. 1, 2 and 3 thereof, there is shown a switch structure similar to that of Fig. 1 of my patent above referred to and which embodies a casing 10 of insulating material and in which are embedded two arcuate shaped electrodes 11 and 12. The electrodes 11 and 12 have terminals 13 and 14, respectively which may be connected in a lighting or ignition circuit including the battery and ground of an automobile. In this case however, the terminals should have flexible leads for reasons later apparent.

The casing is provided with diametrically spaced vertical channels 15 (Fig. 2) which are preferably of a depth equal to the diametrical width of the electrodes and which are of a width equal to the spacing between these electrodes and such channels may extend through the length of upper and lower portions of the closed chamber formed in the casing 10.

A piston 16 is reciprocably mounted in the casing and is normally disposed completely, immersed in a current conducting fluid 16^a, and such piston is preferably formed with its top and bottom ends conoid or rounded, as shown at 16^b.

Through this formation of piston a retentive reservoir for a portion of the conducting fluid is always provided below the piston irrespective of how the switch is turned in vertical operating position of the casing. This reservoir cooperates with the channels 15 to maintain a supply of conducting fluid between the end of the electrodes 11 and 12 under operating conditions wherein the axis of the casing is deflected from the vertical.

As indicated in Fig. 1, the piston is normally in circuit closing position with the volume of fluid within the space immediately above the piston and between the opposed faces of the electrodes 11 and 12 so as to bridge the gap between the ends of said spaced electrodes and thereby complete the circuit between the terminals 13 and 14. If the piston is raised from this normal position to occupy the upper end of the vertically disposed casing, the volume of fluid is such that it will assume a level slightly below the electrodes and thus the circuit may be interrupted at will in this manner. For this purpose the piston 16 is provided with a cylindrical rod member 17 having a ball-like enlargement 18 at its upper end and handle portions 19, extending outwardly from the ball-like enlargement.

The chamber of the casing is closed at its upper end by a plate 20 and a superposed plate 21 which are rigidly held together by bolts 22 which extend into the walls of the casing, the plate 20 being provided with a suitable packing gland 23 for the cylindrical piston rod 17.

As it is desired to retain the piston at various elevations within the chamber of the casing a pair of spring steel strips 24 are each provided with cooperating corrugations as at 25, to provide vertically spaced and horizontally opposed ball receiving sockets for holding ball 18 in desired vertical positions.

As shown these strips 24 are engaged and secured to the plate 21 by the bolts 22 which maintain the same in horizontally spaced apart positions a distance substantially equal to the diameter of handle 19, for reasons later to appear.

A base member 27 receives or is otherwise formed rigid with the lower end of the casing 10. As shown in Fig. 1 the cup-like base member, is maintained rigid with the casing by means of a set screw 28. In either case, however, the base member 27 is pivotally or swivelly mounted on a

support by means of a bolt 29 which extends through the base 30 co-axial with piston rod member 17. A bowed leaf spring 31 has its ends retained and guided by pins 32 depending from the support 30, and a nut and washer 33, 34 are received by the bolt 29 for tensioning the spring to provide the desired frictional contact between base member 27 and support 30 for normally holding the casing in any pre-determined position, angularly about its axis. The leaf spring 31 may be threaded to receive bolt 29 and washer 34 and nut 33 would serve as a locking device in maintaining a constant tension.

As is fully disclosed in my aforesaid patent, the 15 conducting fluid 16^a normally bridges the gap between the electrodes 11 and 12 and thereby completes the circuit between the terminals 13 and 14, when the piston is in its normally lowered position, also that the circuit will be automatically broken should the casing tilt or tip over either to the right or left of (Fig. 1), i. e., substantially in the plane of the terminals 13 and 14 or at right angles to the planes of the contacts of the electrodes. This is due to the fact that the conducting fluid will then rest within the opposite end of the chamber of the casing (or in the hollow of but one of the electrodes) and will thus not reach a level in the chamber to bridge the gap between the electrodes. In this 20 latter tilted position however, the circuit is capable of being manually closed by raising the level of the fluid in the chamber and into electrode bridging position by pulling the piston 16 through the body of conducting fluid to the other 25 end of the casing chamber by means of the rod 17 and handle 19. It will thus be clearly observed that upon tilting automatic breaking of the circuit will occur only upon overturning of the casing 10 substantially in the plane of the 30 axis of the terminals 13 and 14 whereby the opposed plane contact surfaces of the electrodes will be in horizontal planes or in equally spaced relation to the fluid level in such overturned position. It is to be particularly noted that the 35 circuit may be closed after having been broken in the manner above described by rotation of the electrodes with respect to the base.

Should the casing 10 overturn in a plane at right angles to that indicated in Fig. 2 so that the circuit would not be automatically broken, I 40 have now provided means whereby the electrodes may be shifted to the position of Fig. 3 with the terminals 13 and 14, substantially in the plane of such overturning movement. This variable positioning of the electrodes for effective automatic 45 breaking of the circuit upon overturning of the casing 10, as occasioned by a like movement of an automobile on which the switch may advantageously be used, is readily effected by the swivel mounting of the casing and the spacing of the strips 24 as above described. The vertical guide slot provided by the spaced portions of the corrugated steel strips 24 cooperates with the handle 19, so that the casing may be readily rotated 50 or swivelled according to the direction in which the casing may be overturned.

It is to be particularly noted that the two laterally extending portions of the handle 19 are always at right angles to the terminals 13 and 14, and thus may serve an accurate gauge and guide to the operator since it needs only be turned at right angles to the direction of overturning movement of the casing for effectively breaking of the circuit. If desired, however, the parts may be so arranged that the handle 19

may be positioned in the plane of the terminals 13 and 14, in which instance the casing only be turned in the direction of overturning movement of the casing.

By the arrangement above described, the handle 19 not only functions to adjust and position the piston 16 in circuit closing and breaking positions within the chamber of the casing but it also acts to rotate the casing about its axis on the bolt 29, in either direction as indicated by the arrows in Fig. 2, and to any angular position about its axis as indicated by dot-and-dash lines in Fig. 2.

In Figs. 4 and 5 is illustrated a modified embodiment of the invention wherein the piston and pivotal movement of the casing are effected by separate means. This arrangement may be found satisfactory in certain instances but would not be as efficient as the structure of Fig. 1, particularly upon sudden overturning as occasioned by an automobile.

In Fig. 4, a switch similar to that of Fig. 3 in my patent is illustrated and which embodies a casing 10^a enclosing an inner chamber having a tapered inner wall 36. The electrodes 37 and 38, of this form have complementary tapered portions as at 39 and 40, portion 40 being contiguous with wall surface 36. The upper wall portion of this casing has a cylindrical restricted portion 42^a adapted to receive the elongated cylindrical portion 41 of the closure member 42. The inner surface of the portion 41 is shown inwardly tapered as at 43 and is contiguous with the tapered portions 39 of the electrodes 37 and 38.

Closure member 42 has a central opening 44 through which an operating rod 45 passes, the rod carrying a piston 46. Above the opening 44 there is provided a packing gland 47 and formed integral with the closure member there is shown an extension 48 in which is threaded a closure plug 49.

The plug 49 is counter bored and this bore tightly receives the end of the flexible tube 50 through which rod 45 extends and which operates on the principle of a Bowden wire.

The piston 46 has upper and lower tapered portions 51 and 52 corresponding to the upper and lower tapered walls 43 and 36 of the chamber within the casing.

The form of switch operates substantially in the same manner as that of Fig. 1 except that the piston may be adjusted to any pre-determined vertical position. This Bowden wire type is particularly adapted for use in remote control.

Provision is made for rotation or swivelling of casing 10^a, for the purpose above set forth and is accomplished by means of a flat base member 54 secured as by screws 55 to the bottom of casing 10^a. This base member is pivotally supported on a bolt 56 co-axial with the casing, the bolt extending through a support 57 and having a nut and washer 58 and 59 for compressing a bowed leaf spring 60 for maintaining frictional contact between the base member 54 and support 57 for reasons above set forth in connection with Figs. 1 to 3.

The base member 54 is provided with a boss 61 having a transverse bore to receive one end of a Bowden wire 62 extending through a flexible member 63 and which is retained in the boss bore by means of a set bolt 64. With this modified arrangement the casing 10^a may readily be swivelled on its axis by the wire 62 and the plunger may be vertically controllable by means

of the rod 45 in any rotary position of the casing.

A modified arrangement of switch casing 10^b is rotatably supported on a dish-form base 66 by means of a bolt 67 retained in the casing by means of a laterally disposed bolt 68 having a comparatively large head 69. The bolt 67 extends through a bowed leaf spring 70 and has its head 71 engaging said spring and rotatable relative thereto. The head 69 is bored as at 72 to receive a Bowden wire to be retained in position by means of a set bolt 73.

In Figs. 7 and 8 is disclosed a modified arrangement of piston operating and casing rotating means. As shown in these figures the switch casing 10^c is provided with a single corrugated spring steel strip 75 defining a vertical loop member similar to that shown in Fig. 1 and having opposed legs 76 secured to the casing by bolts 77. The piston rod 78 in this arrangement is provided with a cylindrical member 79 engageable in opposed concave portions of the spring strip loop and a further rod 80 projects upwardly from member 79, through the upper end of the loop and is provided with an operating handle 81. This form is believed to be most convenient for unit operation particularly from the seat of a vehicle, since the rod 80 may project up through the floor board and on which rod the elongated cylindrical handle 81 extends in the plane of the axis of the electrode terminals. A ready means of rotatively setting the casing is thereby provided for efficient circuit breaking irrespective of the direction of tilting movement of the casing in the event of overturn of the vehicle.

In Figs. 9 and 10 is disclosed a further modified embodiment of means for both actuating the piston and imparting rotation to the switch casing about its axis. The switch casing 10^d is here shown embraced by a sleeve 82 having a slot in the side wall thereof and which slot includes a vertical portion 83 having three lateral extensions 84 for selectively receiving a headed pin 85 projecting from the exterior wall of casing 10^d. The upper end of sleeve 82 is dome shaped as at 86 and has a ball 87 suitably secured thereto. A piston rod 88 carrying piston 89 at its lower end, is rigidly secured in an aperture in the ball 87 by means of a set screw 90 so as to be manually operable thereby. The sleeve is recessed at 91 to clear the terminals 13, 14 and the remainder of the structure is the same as that of Fig. 1, and is indexed accordingly. With this arrangement, the piston may be readily moved by first slightly turning the sleeve to bring the pin 85 into the vertical portion 83 of the slot, the extensions 84 serving to normally retain the sleeve and piston in selected vertical positions, rotation of the casing may then be accomplished by engagement of the pin 85 with the ends of extensions 84 and remote side of slot portion 83.

While the foregoing described embodiments of the invention each provide manual controls for the rotation or swivelling of the switch casing which will prove satisfactory in many uses of the switches, an automatic means for rotating the casing to proper position for circuit breaking is preferable in such uses of the switch as in automotive vehicles, motor boats and the like, wherein the overturning is sudden and there is usually neither time nor any accurate means provided for ascertaining the correct angular position of the casing for manually effecting proper interruption of the circuit.

For such uses therefore I have provided in Figs. 11 and 12, an embodiment of the invention

wherein the switch casing 10^e is automatically rotated for automatic breaking of the circuit regardless of the direction of overturning of the casing and which embodiment is particularly effective for the uses stated. For this purpose a base member 93 is rigidly secured to the lower end of the casing 10^e, as by means of a set screw 94, and the base member is so formed as to provide an upper ball bearing race and a companion lower race 95 secured to a support 96, as by bolts 97. Bearing balls 98 are retained between the races by means of a pivot bolt 99 having its upper end rigidly secured to the member 93 and thence extending through the member, and a bearing sleeve 109 and terminating below the support 96.

An arm 101 is secured to the bolt 99 by nut 102 and associated washers carried by the bolt for rotation therewith. A weight 103 is supported by the free end of the arm and this arm is normally held in the plane of the electrode terminals 13, 14 by relatively inverted V-shaped spring 104 depending from the support 96 at each side of bolt 99 for yieldably engaging arm 101 and holding the casing in the proper normal position which is as shown in Fig. 11, or with the arm engaging the other spring 104.

The casing 10^e is preferably provided with piston lifting means similar to that of Fig. 7 including a corrugated strip 105 and handle 106. This form as well as that of Fig. 1 also provides for manual rotation of the casing, whereby it may readily be set into normal operating position.

Since the arm 101 is normally in the plane of terminals 13, 14 such terminals will be automatically rotated into the plane of overturning movement of the casing by the weight 103 which obviously will fall into such plane by action of gravity.

A similar arrangement is shown in Fig. 13 modified by the substitution of an arm 108 for the arm 101. The arm 108 is shown pivotally connected at one end thereof to a lug 109 extending from the base member 93 and a bowed spring 110 is secured to the lug 109 and bears on the arm 108 to yieldably urge it downward toward the support 96.

The support 96 is provided with a pair of oppositely disposed relatively shallow spherical sockets 111 for selectively receiving a ball 112 rotatably supported on the arm 108, in either normal operating position of the switch casing.

While I have shown different forms of cooperating electrodes and pistons as in Figs. 1 and 4, it is to be noted that they may be reversed and that either form or even other forms as shown in my patent may be used in combination with the casing swivelling structures herein disclosed.

Having thus described the invention in accordance with certain preferred embodiments, what is claimed is:

1. In a safety switch, a cylindrical casing having walls defining a closed chamber therein, means pivotally supporting said casing in normally vertical position, electrodes mounted in spaced relation in said walls intermediate the opposite ends of said chamber and providing a gap therebetween substantially in the vertical axial plane of the casing, means associated with said casing and its pivotal mounting for rotating said casing on its axis to position the plane of the electrode gap at substantially right angles to any direction of tilting movement of said casing toward a horizontal position upon overturn-

ing thereof, conducting fluid within said chamber of a volume to normally bridge said gap when the casing is in its normally vertical position and to recede into said chamber out of bridging relation with said gap upon rotation and tilting of said casing in any of said directions, and manually operable means movably mounted within said chamber and coacting with said fluid therein to cause the same to again bridge said gap while said casing is tilted in any overturned position.

2. A safety switch according to claim 1 wherein said means for pivotally supporting the casing comprises a base member rigidly connected with the lower end of the casing, a pivot bolt coaxial with the casing extending through said base member and a support therefor, and yieldable means holding said base member in frictional engagement with said support while permitting relative rotation therebetween.

3. A safety switch according to claim 1 wherein said means for pivotally supporting the casing comprises a base having a casing support mounted thereon, a headed pivot bolt coaxial with the casing extending vertically through said base and into said casing, a leaf spring disposed between said base and the head of said bolt for urging said casing into frictional contact with said base, and means anchoring said casing to said casing support to hold the casing in axial position upon the base.

4. A safety switch according to claim 1 wherein said manually movable means in the chamber comprises a piston having an operating rod extending through the upper end of the casing, and wherein said means for rotating the casing comprises a member rigid with the rod and means supported by the casing and engageable by the member for rotation of the casing upon rotation of the rod.

5. A safety switch according to claim 1 wherein said manually movable means in the chamber comprises a piston having an operating rod extending through the upper end of the casing, a pair of flexible spaced corrugated strip portions secured to the upper end of the casing, a member rigid with the rod and having rounded sides engageable within opposed recesses of the corrugations to maintain the rod in vertical adjusted position, and wherein said means for rotating the casing comprises a rod operating handle extending diametrically of the member and projecting between adjacent edges of the strips to effect rotation of the casing upon movement of the handle around the axis of said rod.

6. A safety switch according to claim 1 wherein said manually movable means in the chamber comprises a piston having an operating rod projecting through and above the top of the casing, a member secured to the upper end of the rod for operating same and means for selectively retaining the piston in different positions in the chamber and for effecting said rotation of the cylinder comprising a sleeve embracing the cylinder and secured to said ball, a headed pin projecting from the outer wall of the cylinder, and a slot in the sleeve including a vertical portion and lateral portions from one side thereof, the vertical portion permitting movement of the piston in the chamber, the lateral portions selectively receiving the pin to hold the piston in any selected position, and the ends of the lateral portions and opposed side of the vertical portion being engageable with the pin upon rotation of the sleeve to impart rotation to the cylinder.

7. A safety switch according to claim 1 wherein said means for pivotally supporting the casing comprises a base member rigid with one end of the casing and conformed to provide an upper bearing race, a lower bearing race secured to a support, bearing balls operatively positioned between the races, a pivot bolt secured at its upper end to said base member and projecting through

5 and below said support, an elongated arm having one end thereof secured to said base member and extending normal to said plane of the gap, a weight on the other end of said arm, and friction means associated with said base and support for retarding free rotation of said arm in normal vertical operating position of said casing.

FRED COLBY.
